UNITED STATES PATENT OFFICE.

GEORGE ROCKWELL, OF MERIDEN, CONNECTICUT.

DESIGN FOR A HANDLE FOR SPOONS, &c.

SPECIFICATION forming part of Design No. 25,693, dated June 30, 1896.

Application filed May 27, 1896. Serial No. 593,346. Term of patent 7 years.

To all whom it may concern:

Be it known that I, GEORGE ROCKWELL, of Meriden, in the county of New Haven and State of Connecticut, have invented a new Design for the Handles of Spoons, Forks, and Kindred Articles; and I do hereby declare the following, when taken in connection with the accompanying drawing and the letters of reference marked thereon, to be a full, clear, and exact description of the same, and which said drawing constitutes part of this specification, and represents a face view of a handle embodying my design.

My invention relates to a new and original design for the handles of spoons, forks, and kindred articles of table-service; and the design consists in the configuration and ornamentation of the handle, as herein shown and described.

My newly-designed handle comprises a long gourd-shaped medallion A, arranged with its smaller end extending inward. It is flanked on either side by three long frond-like scrolls a, a', and a'', the spaces between the scrolls

a' and a'' being occupied with small shell-like figures a''. The tip of the handle is formed by a large shell-like ornament A', interposed between the enlarged ends of the scrolls a. The smaller inner end of the medallion A is flanked by scrolls a'', one of which overlies it. Still further inward on the handle are scrolls a''' of leaf-like form. Thence inward the edges of the handle are flanked by ribs a'', which terminate in a scroll a''. The design for the handle as a whole partakes of the 35 rococo form of decoration now in vogue.

I claim—

The design for the handles of spoons, forks and kindred articles, as herein shown and described.

In testimony whereof I have signed this specification in the presence of two subscribing witnesses.

GEO. ROCKWELL.
